Application June 13, 1935, Serial No. 26,366

6 Claims. (Cl. 260—108)

This invention relates to a process for separating and recovering naphthenic acids from petroleum hydrocarbons, and especially to a process for recovering purified naphthenic acids 5 from the residues obtained by vacuum-distilling naphthene base lubricating oil stocks with caustic soda or equivalent alkalies.

More specifically, our invention contemplates the segregation of the distillation residues obtained by vacuum-distilling naphthene base lubricating stocks in the presence of alkali metal hydroxides, and emulsifying the same with water in the presence of a low boiling hydrocarbon, acidulating the so-formed emulsion with a mineral acid until the naphthenates, contained in the distillation residues, are decomposed and the free naphthenic acids liberated. The acidulated mixture is then permitted to remain quiescent whereby there are formed two layers, the low comprising 10 water, tar, salts, and free mineral acid, while the upper supernatant layer consists essentially of crude naphthenic acids dissolved in the diluent low boiling hydrocarbon. The latter is then subjected to treatment as by distillation, whereby the crude naphthenic acids are freed from the low boiling petroleum hydrocarbon diluent, whereupon the crude acids are subjected to a vacuum distillation to produce naphthenic acids of a high degree of purity.

Naphthenic acids are cyclic organic acids which are present in varying amounts in a large number of crude petroleums of the naphthene base type. In the typical American crude oils, only minute percentages are present in the low viscosity derivatives, such as naphtha, kerosene and low boiling lubricating oils, the most of the acids being found in higher boiling fractions. In the refinery practice, it is customary to subject the topped crude to vacuum distillation in the presence of alkalies such as caustic soda, whereby the naphthenic acids are converted into the corresponding non-vaporizable alkali salts. The residues remaining in the vacuum stills, after substantially all of the distillable fractions have been 35 vaporized, comprise essentially the heavy hydrocarbon oils, tars, and the aforementioned naphthenic acid salts. This mixture is spoken of in refinery terminology as lubricating still bottoms or lubricating still residues.

Various methods have been proposed for recovering naphthenic acids in a purified form from the lubricating still bottoms, with which they are associated, in the form of sodium salts. Among these, one of the most efficient appears to be the 50 extraction of the sodium naphthenates from the

lubricating still bottoms by means of alcohol and thereafter acidulating the extracted sodium naphthenates with sulfuric acid to liberate the corresponding naphthenic acids. However, this method is generally recognized to be uneconomical because of the high cost of the extracting solvent. By the method which we have discovered, we are enabled to prepare naphthenic acids of a high degree of stability and purity without the disadvantage of employing expensive reagents or solvents.

We have found that the naphthenic acids may be separated directly from the lubricating still bottoms by emulsifying the same with water, and then adding to the so-formed emulsion a low boiling diluent petroleum hydrocarbon which serves certain definite and important functions which will be fully discussed hereinafter. The mixture formed in this way is treated with a sufficient quantity of sulfuric acid to decompose 20 all of the sodium naphthenate present and to thereby liberate the corresponding naphthenic acids. When the acidulation step has been completed, the mixture is permitted to remain quiescent in order to permit settling of the water 25 solution of sodium sulfate and free sulfuric acid and the precipitation of the tars which are associated with the sodium naphthenates in the lubricating still bottoms. The supernatant oily layer comprises a solution of the liberated naphthenic acids dissolved in a diluent low boiling hydrocarbon. This oily layer is then drawn off and is subjected to distillation to remove the diluent, and the remaining naphthenic acids 30 may then be further purified by means of a distillation carried out under a high vacuum, whereby it is possible to produce fractions of naphthenic acids having different gravities and boiling points, all of which are characterized by their 35 high degree of purity.

Our invention will be fully understood from the following description taken in connection with the drawing which shows in diagrammatic sectional elevation an apparatus which may be used with advantage for carrying out the invention.

The numeral 10 designates a fractionating tower, into a lower point of which there is connected the line 11, controlled by the valve 12. The top of the tower is connected through the line 14, and the valve 15, with the coil 16 of the 50 condenser 17. The condenser coil discharges through the line 18, controlled by the valve 19, into the separator 20. The vapor space of this separator is connected with a suitable evacuating apparatus, such as a vacuum pump or jet. The 55

bottom of the separator is connected by line 21, and valve 22, with pump 23, which discharges through line 24, and valve 25, into the storage tank 26.

5 The bottom of the fractionating tower 10 is connected through the line 27, valve 28, pump 29, and valve 30, with the agitator 31, preferably provided with a conical bottom. It is also provided with a stirrer 32, which serves to agitate 10 the contents. The numerals 33, 36, and 39 designate three storage tanks for the storage, respectively, of sulfuric acid, water and diluent hydrocarbon. These tanks are connected, respectively, to the agitator 31, by the lines 34, 37, and 15 40, equipped with suitable control valves. The bottom of the agitator 31 is connected by means of the line 42, and valve 43, with the settling chamber 45. This may, with advantage, be an elongated vessel provided with a conical bottom, 20 from which the line 46 leads to a sump or other disposal facility. This line is provided with a float-controlled valve 47, for controlling the level of aqueous liquor within the separator. The separating chamber 45 is connected by the line 49, 25 and valve 50, to the intake side of the pump 51. The outlet side of the pump is connected through the line 52, and valve 53, with the coil 54 of the preheater 55. This coil discharges through the line 56, and expansion valve 57, into a lower part 30 of the fractionating tower 58. This is provided at the bottom with the drawoff line 59, controlled by the valve 60, and at the top with a cooling coil 61, which serves to supply reflux liquid during operation. The top of the fractionating tower is connected by line 63, and valve 64, with the coil 65, of the condenser 66. The condenser coil discharges through the line 67, and valve 68, into the receiving tank 69. This tank serves a dual purpose. It acts as a receiving 35 tank for the diluent hydrocarbon oil, which has been distilled from the naphthenic acids, and serves also as a settling chamber wherein any water, which is distilled over with the distillate, is separated therefrom. The water drawoff 40 line 70, leading from the bottom of the receiving tank 69, has a float-controlled valve 71, which serves to maintain a small but constant level of water within the receiving tank. The top of the receiving tank is connected by the line 72, controlled by the valve 73, with the pump 74. This pump discharges through the line 75, and the 45 valve 76, into the diluent hydrocarbon storage tank 39.

The drawoff line 59, at the bottom of the tower 58, connects with the intake side of the pump 77, which discharges through line 78, and valve 79, into the coil 80, of the preheater 81. The outlet side of the preheater coil is connected through the line 82, and expansion valve 83, into 60 a lower point of the fractionating tower 84. This tower is preferably so constructed as to permit fractionation therein at low pressures. The bottom of the tower is provided with a drawoff line 86, and valve 87, leading to suitable 65 storage. The cooling coil 88, at the top of the tower, provides for the formation of reflux liquid. From the top of the tower, the vapor line 89, provided with valve 90, connects with the coil 91, of the condenser 92, which discharges 70 through the line 93, controlled by the valve 94, into the receiving tank 95. The vapor space of this receiving tank is connected through line 96, and valves 97 and 98, with a vacuum pump or other evacuating means. The bottom of the 75 receiving tank 95 is connected through the line

100, and valve 101, with the pump 102, which discharges through the line 103, and valve 104, into the atmospheric storage tank 105.

The line 107, provided with valve 108, connects an intermediate portion of the fractionating tower 84, with the cooling coil 109 of the cooler 110. The outlet side of the cooling coil is connected by means of the line 112, and valve 113, with the vacuum receiving tank 114. The upper portion of this receiving tank is connected 10 through the line 115, and the valve 116, with the line 96, at a point intermediate the valves 97 and 98. The bottom of the vacuum receiving tank 114 is connected through line 118, pump 120, and line 121, with an atmospheric storage 15 tank 123.

In a typical operation of the process, in connection with the hereinbefore described apparatus, a lubricating oil stock is reacted at an elevated temperature with an alkali metal hydroxide 20 such as, for example, sodium hydroxide, sufficient to convert the naphthenic acids present in lubricating oil stock into sodium naphthenates. The heated mixture is discharged through the line 11, into the fractionating tower 10, which is 25 maintained under a high vacuum, and the vaporizable fractions are taken off as distillates. Although the accompanying figure shows provision for taking off only an overhead fraction, it is to be understood that one or more side 30 stream fractions may be drawn off.

The non-volatile residual fraction, which is formed, consisting of sodium naphthenates, tars and heavy relatively non-vaporizable oils, and heretofore spoken of as lubricating still bottoms 35 or lubricating still residues, is drawn out of the bottom of the fractionating tower 10, by the pump 29, and delivered into the agitator 31, where it is agitated with two or three times its volume of water until the components are completely dispersed in the water. To this emulsion, there is added a quantity of diluent hydrocarbon oil which may vary from one to two times the volume of emulsion. Sufficient sulfuric acid is added to the mixture until the free alkali is neutralized 40 and the sodium naphthenates are decomposed. The mixture is then passed into the settling chamber 45, where the aqueous liquor, containing free sulfuric acid and sodium sulfate, together with tars and the like, settle out, leaving 50 a supernatant layer of a solution of naphthenic acids in the diluent hydrocarbon oil which layer may be washed, if desired, with water. This solution is then delivered into the preheater 55, where it is heated to a temperature above the boiling 55 point of the diluent hydrocarbon oil. The heated mixture is flashed into the fractionating tower 58, where substantially all of the diluent hydrocarbon oil is vaporized. The vapors are conducted 60 to the condenser 66, where they are condensed and then pumped from the receiving tank 69, into the storage tank 39.

The non-vaporizable residue, which collects as a pool at the bottom of the tower 58, is drawn off through the line 59, by means of the pump 65 71, and delivered by it under superatmospheric pressure into the preheater 81, where it is raised to an elevated temperature, preferably in the range of from 500° to 700° F. The heated mixture is then delivered into the fractionating tower 70 84, which is maintained under a high vacuum, where the naphthenic acids are substantially vaporized and pass upwardly through the tower. Cooling is supplied at an upper point in the tower 75 in order to cause the formation of reflux liquid. 75

The lower boiling naphthenic acids are drawn off as vapors from the top of the tower, while the higher boiling naphthenic acids are drawn off at lower points, only one of which, however, is shown in the drawing. The naphthenic acid vapors, which are drawn off from the top of the tower, through the vapor line 89, are delivered into the condenser 92 where they are condensed. The condensate is delivered into the separatory chamber 95, the vapor space of which is connected with a vacuum pump or other means for evacuating the last distillation stage. The liquid space of the separatory chamber is connected by means of the line 100, with the pump 102, which serves to withdraw the collected condensate from the separatory chamber and deliver it into the storage tank 105. The side stream of liquid naphthenic acids, which is drawn off through the line 107, is handled substantially in the same manner as the vapors of naphthenic acids taken off from the top of the tower. They are cooled in the cooler 110, from which they pass into the separatory chamber 114. From this point they are pumped by means of the pump 120, into the storage tank 123.

In carrying out the method of purification which forms the basis of this invention, the diluent hydrocarbon oils are used in the steps which involve the decomposition of sodium naphthenates and the subsequent distillation operation. It serves several functions, the most important of which is to make possible a rapid and effective decomposition of the sodium naphthenates by the mineral acid employed. It also acts as a solvent for the naphthenic acids which are liberated and, in this manner, enables their separation from the aqueous liquor which is formed as a by-product of the neutralization reaction. In the succeeding step, which involves the separation of the naphthenic acids from the diluent hydrocarbon, the diluent acts as a distillation carrier for some of the unstable hydrocarbons which are normally associated with impure naphthenic acids, making possible their vaporization and consequent separation during the distillation operation.

For this purpose, various types of petroleum hydrocarbons may be used, including kerosene, high boiling naphtha or low boiling naphtha such as precipitation naphtha or cut-back naphtha. Generally speaking, it is desirable that the diluent hydrocarbon oil be comparatively low boiling so that it may be separated effectively and completely from the naphthenic acids by distillation.

For the most effective application of the present process, several important considerations must be recognized. The contaminating impurities in commercial naphthenic acids consist essentially of high boiling oils which apparently are unstable and gradually oxidize, thereby imparting color and other undesirable features to the naphthenic acids. In order that the percentage of these undesirable oils may be kept down to a minimum, it is desirable that the distillation of the naphthene base oils, in the presence of caustic soda, be carried out under the highest vacuum that is economically possible, thereby insuring the removal of as much of the oils as possible.

Also, it is essential for the most effective operation of the present process that provision be made for carrying out the final fractionation of the naphthenic acids under as ideal distillation conditions as is possible. This includes the provi-

sion of a carefully designed fractionating tower, preferably lagged with heat insulating material, so as to conserve as much of the heat as possible, and to prevent unduly high condensation within the fractionating vessel. Also it is desirable to use corrosion resistant materials for the fractionating and condensing equipment. Metals, which are useful for this purpose, are aluminum, chromium and the various types of stainless steels which are now available on the market. It has been found experimentally that, by employing the aforementioned materials in the fractionating and even in the condensing and cooling apparatus, the products have a better color stability than normally obtained when iron or steel materials are employed in the construction of the distillation equipment. Although no theoretical explanation is offered, it is thought that the naphthenic acids react with iron, thereby forming the dark brown iron naphthenate which, if carried over into the distillate stream, discolors the product and renders it more susceptible to oxidation.

Obviously many modifications and variations of the invention, as hereinbefore set forth, may be made without departing from the spirit and scope thereof, and therefore only such limitations should be imposed as are indicated in the appended claims.

We claim:

1. The method of recovering naphthenic acids of a high degree of purity from petroleum hydrocarbon oils, which comprises distilling the oils in the presence of an alkali to remove distillate fractions thereof and form a residual oil fraction containing the neutralized naphthenic acids, emulsifying the residual fraction with water in the presence of a diluent light oil, acidifying the so-formed emulsion to liberate the naphthenic acids therein, subjecting the acidified mixture to settling to form a supernatant layer comprising a solution of the liberated naphthenic acids in the diluent oil, separating and removing the supernatant layer, separating therefrom the diluent oil, and then vacuum-distilling the remaining naphthenic acids to segregate naphthenic acids of the desired purity.

2. The method of recovering naphthenic acids of a high degree of purity from the petroleum hydrocarbon oils in which they are dissolved, which comprises vacuum-distilling the oils in the presence of an alkali metal hydroxide to remove distillate fractions thereof and form a substantially non-vaporizable residual fraction containing the alkali metal salts of the naphthenic acids, emulsifying the residual fraction with water in the presence of a diluent light oil, acidifying the so-formed emulsion to decompose the alkali metal naphthenates and to liberate therefrom the naphthenic acids, then subjecting the acidified mixture to settling to form a supernatant layer comprising a solution of the naphthenic acids in the diluent oil, separating the supernatant layer and subjecting it to distillation to remove the diluent oil and to form a residual fraction comprising naphthenic acids, and then subjecting the residual naphthenic acids to vacuum distillation to segregate the desired naphthenic acids.

3. The method of recovering naphthenic acids of a high degree of purity from topped naphthene base crude oil in which they are dissolved, which comprises vacuum-distilling the crude oil in the presence of an alkali metal hydroxide to form distillate fractions thereof and form a substan-

tially non-vaporizable residual fraction containing the alkali metal salts of the naphthenic acids, emulsifying the residual fraction with water in the presence of a diluent light oil, acidifying the 5 so-formed emulsion with a mineral acid to decompose the alkali metal naphthenates and to liberate the naphthenic acids, then subjecting the acidified mixture to settling to form a supernatant layer comprising a solution of the naphthenic acids in the diluent oil, separating the 10 supernatant layer and subjecting it to distillation to remove the diluent and to form a residual fraction comprising naphthenic acids, and then subjecting the residual naphthenic acids to vacuum 15 distillation to segregate the desired naphthenic acids.

4. The method of recovering substantially oil-free naphthenic acids from topped naphthene base crude oil in which they are dissolved, which 20 comprises vacuum-distilling the crude oil in the presence of an alkali metal hydroxide to remove substantially acid-free distillate fractions thereof and form a substantially non-vaporizable residual fraction containing alkali metal salts of the 25 naphthenic acids, emulsifying the residual fraction with water in the presence of a diluent light oil, acidifying the so-formed emulsion with strong sulfuric acid to decompose the alkali metal naphthenates and to liberate the naphthenic acids, 30 subjecting the acidified mixture to settling to form a supernatant layer comprising a solution of the naphthenic acids in the diluent oil, separating the supernatant layer, subjecting it to distillation to recover the diluent oil and to form 35 a residual fraction comprising naphthenic acids, and then subjecting the latter to vacuum distillation to segregate naphthenic acids of the desired degree of purity.

5. The method of recovering substantially oil-free naphthenic acids from topped naphthene base crude oil in which they are dissolved, which comprises vacuum-distilling the crude oil in the presence of an alkali metal hydroxide to remove 5 substantially acid-free distillate fractions thereof and form a substantially non-vaporizable residual fraction containing alkali metal salts of the naphthenic acids, emulsifying the residual fraction with water in the presence of naphtha, acidifying the so-formed emulsion with strong sulfuric acid to decompose the alkali metal naphthenates and to liberate the naphthenic acids, 10 subjecting the acidified mixture to settling to form a supernatant layer comprising a solution of the naphthenic acids in the naphtha, separating the supernatant layer, subjecting it to distillation to recover the naphtha and to form a residual fraction comprising naphthenic acids, and then subjecting the latter to vacuum distillation 15 to segregate naphthenic acids of the desired degree of purity.

6. The method of recovering naphthenic acids of a high degree of purity from petroleum hydrocarbon oils, which comprises distilling the oils in 20 the presence of an alkali to remove distillate fractions thereof and form a residual fraction containing the alkali soaps of the naphthenic acids, decomposing the naphthenic acid soaps with a 25 mineral acid in the presence of water and a diluent light oil, separating and removing the diluent oil solution of the naphthenic acids, removing therefrom the diluent, and then vacuum-distilling the remaining naphthenic acids to segregate 30 acids of the desired purity.
